UNITED STATES PATENT OFFICE.

HOWARD LYON, OF GLOUCESTER CITY, NEW JERSEY, ASSIGNOR TO WELSBACH LIGHT COMPANY, OF GLOUCESTER, NEW JERSEY, A CORPORATION OF NEW JERSEY.

PROTECTING DEVICE FOR INCANDESCENT GAS-LAMPS.

1,251,547.

Specification of Letters Patent.

Patented Jan. 1, 1918.

Application filed July 23, 1914. Serial No. 852,619.

To all whom it may concern:

Be it known that I, HOWARD LYON, a citizen of the United States, residing at Gloucester City, Camden county, New Jersey, have invented a new and useful Improvement in Protecting Devices for Incandescent Gas-Lamps, of which the following is a full, clear, and exact description, reference being had to the accompanying drawings, forming part of this specification, in which:

Figure 1 is a side view partly broken away, showing my invention applied to one form of lamp.

Fig. 2 is a perspective view of the upper canopy or protector.

Fig. 3 is a plan view of the lower canopy or protector.

Fig. 4 is a sectional elevation showing the lower canopy or protector applied to another form of lamp, and

Fig. 5 is a plan view of the canopy or protector of Fig. 4.

My invention has relation to safety or protecting means for the glassware and fixtures of incandescent gas lamps of the inverted type; and is designed to provide means of simple and efficient character for preventing the heat from the lamp burners from discoloring the fixture, as well as for breaking up the heat column in such a way as to largely dissipate the heat before it strikes the ceiling. Also to provide a protector or canopy which can be placed directly below the mantles for the purpose of preventing injury to the glassware of the lamp.

While my invention is particularly adapted to the horizontal type of burner for use in indirect and semi-indirect lighting systems described and claimed in my copending application, Serial No. 852,618, filed July 23, 1914, it may be, in all or in part, applied to various other forms of lamps.

Referring first to that form of my invention which is shown in Figs. 1 to 3 inclusive, the numeral 2 designates the manifold of a suspended lamp such as is employed in indirect systems of lighting. This manifold has a plurality of depending burners 3, having the incandescent mantles indicated at 4. 5 designates the bowl or glassware of the lamp, which is supported in any suitable way within the supporting ring 6 and which

ring is shown as suspended by the members 55 7. One of these members may be made hollow to serve as the gas supply pipe which communicates with the mixing tube 8 leading to the manifold 2.

9 designates an upper canopy or protector 60 which is placed over the manifold in the manner shown in such a way as to form a deflector, preventing the heated products of combustion from the burners from coming in contact with the supporting members 7 65 and thus discoloring them. It also acts to deflect and dissipate the heat. This canopy or protector may be of any suitable character. It is preferably, however, formed of transparent or semi-transparent or translucent material, such as mica, held in a suitable frame 10 having the supporting arm 11 which may be secured to a collar 12 on the mixer pipe or tube 8 leading to the manifold. This canopy or protector is preferably 75 of arched form, as shown.

13 designates the lower canopy or protector which is placed below the mantles and between them and the bowl 5. This may also be conveniently supported by an arm 14 80 from the collar 12. It is shown as being of inverted cone form; and in this particular instance composed of a plurality of assembled pieces 15 of mica secured together by pins or eyelets 16.

85 The main purpose of this canopy is to prevent the flame, in case of a broken mantle, from coming in contact with the glass bowl. Its use also tends to lower the temperature of the glass bowl and thereby 90 greatly reduces the breakage. It also facilitates the more prompt and free ignition of the burner from the usual pilot light, (not shown) since it tends to confine the gas delivered by the pilot light tube in the immediate vicinity of the mantles. In case a portion of one of the mantles should drop, this canopy catches it and prevents its falling onto the glassware.

95 Instead of mica, I may use any other suitable material such as fused pure quartz; and in some cases the lower canopy may be made of non-translucent material.

100 The canopies may be supported in various ways; and the upper canopy can be so 105 shaped as to direct the heat products in any desired direction. Various other changes can be made in the details of construction.

and arrangement of the parts without departing from the spirit and scope of my invention.

Thus, in Figs. 4 and 5 I have shown the lower canopy applied to another form of incandescent gas lamp supported from below. In this construction, the canopy shown at 17 is supported below the mantles 18 by a metal collar 19 mounted on the Bunsen tube 20. This collar is shown as having the lugs 21 which engage the body of the canopy; and in Fig. 5 one of these lugs is shown extended, as at 21^a, directly underneath the seam of the canopy, to the upper, outer edge thereof. The purpose of the canopy in this application is the same as in that first described, namely, to protect the glassware 22.

What I claim is:

1. An inverted incandescent cluster lamp having glassware extending below its mantles, a protecting device or canopy arranged between the lower ends of the mantles and the glassware independently of the glassware and having transverse dimensions greater than the mantle cluster, the upper edge of the protecting device being below the body portions of the mantles, said protecting device being of heat-insulating material and arranged to protect the glassware below said protector from the heat of the mantle, said protector being without any substantial openings therein; substantially as described.

2. In an inverted incandescent cluster gas lamp having glassware extending below its mantles a protecting device or translucent canopy of dished form arranged between the lower ends of the mantles and the glassware independently of the glassware and having transverse dimensions greater than the mantle cluster, said protector being of heat-insulating material and protecting the lower part of the glassware from the heat of the mantles, the upper edge of the protector being below the upper parts of the mantles; substantially as described.

3. An inverted incandescent cluster gas lamp, arranged for indirect or semi-indirect

lighting having depending separated suspension members, and a canopy or deflector of arch form arranged above the burners, two of the longitudinal edges of the deflector being approximately straight, while the other two edges are of curved form, the deflector being so positioned that the heat currents are directed outwardly over one of the curved edges between the depending suspension members; substantially as described.

4. An inverted incandescent cluster gas lamp, arranged for indirect or semi-indirect lighting having depending separated suspension members, and a canopy or deflector of arch form arranged above the burners but within the globe or deflector holder, two of the longitudinal edges of the deflector being approximately straight, while the other two edges are of curved form, the deflector being so positioned that the heat currents are directed outwardly over one of the curved edges between the depending suspension members; substantially as described.

5. An inverted incandescent cluster gas lamp, arranged for indirect or semi-indirect lighting having depending separated suspension members, and a canopy or deflector of arch arranged above the burners, two of the longitudinal edges of the deflector being approximately straight, while the other two edges are of curved form, the deflector being so positioned that the heat currents are directed outwardly over one of the curved edges between the depending suspension members; substantially as described.

In testimony whereof, I have hereunto set my hand.

HOWARD LYON.
